UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed March 2, 1923. Serial No. 622,285.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

The invention relates to typewriting machines. More particularly, the invention relates to so-called billing machines in which provision is made for feeding a succession of form-sections in a continuous web, and in a plurality of plies, to the platen, and in 10 which carbon-sheets, secured to a carbon-carrier, are interleaved with the web-plies; the carbon-carrier being mounted in a runway on a supporting structure attached to the platen-carriage to have line-feed movement with the web toward the platen, and to 15 be moved rearward on the supporting structure for clearing the carbons of the leading written form-sections and bringing the carbons into interleavement with succeeding 20 form-sections, at the completion of the typewriting on the leading form-sections. A machine of this general class is shown in United States Letters Patent to Wernery and Smith, No. 1,132,055, dated March 16, 1915. 25 In the machine therein shown, the carbon-sheets are individual sheets secured at their rear ends to blades on the carbon-carriage, and are of a limited and predetermined length, forward from the blades, sufficient 30 to cover the leading form-sections of the work-sheet-plies, and to be gripped with the latter to the platen when the carbon-carrier is in its rearward position preliminary to 35 commencing writing on the leading form-sections.

Carbon-sheets necessarily become worn in use, and new sheets or fresh carbon-areas of the same sheets must be substituted from time to time for the worn ones. The interleavement of individual carbon-sheets with the plies of a multiple work-sheet-web, and the attachment of such sheets to a carbon-carrier, involve time and inconvenience. 45 Rolls of carbon-paper have therefore been substituted on the carbon-carrier for the relatively short individual sheets previously used. Rotary movement of such a roll permits the desired length of sheet to be unwound therefrom and interleaved with the web-plies. The roll may then be locked 50

against rotation, so that, as in the Wernery and Smith patent, the grip of the platen on the interleaved portion of the carbon-sheet will result in forward movement of the carbon-carrier when the platen has line-space 60 movement, and so that rearward throw of the carbon-carrier will shift the interleaved portion of the carbon-sheet rearward along the web-plies. When such interleaved portion of the carbon-sheet becomes worn, the roll may be unlocked and the carbon-sheet drawn forward sufficiently for detachment therefrom of the leading, worn, part, and for replacement of such part by a fresh length unwound from the roll. Obviously, 65 in such use of a carbon roll, the operations of attaching carbon-sheets to the carbon-carrier, and of interleaving the same with web-plies, may be done once and for all—that is to say, unless and until the roll is 70 exhausted or is to be replaced.

The web-plies have, however, heretofore been fed through the carbon-carrier, usually from the rear thereof; and whereas, as in the Wernery and Smith patent, the web-plies may be compactly handled and easily fed and interleaved at the carbon-carrier with individual carbon-sheets held by blades, on the carrier, it has not been found economical as to space required, nor entirely satisfactory as to the feed thereof, to pass the web-plies between the carbon-rolls for interleavement with the carbon-sheets. 80 To avoid the necessity of feeding the web-plies between the carbon-rolls, the latter have been set on the carbon-carrier to the side of the path of the web-plies through the carrier, and the interleavement has been effected forward of the rolls. This expedient, however, has involved a widening, and 85 consequent increase in the weight, of the carrier, and, aside from the additional space required, has thus thrown an additional burden on the platen-carriage, oftentimes resulting in sluggish or unreliable letter-feed action of the latter or in disadvantages arising from the increased inertia of the platen-carriage.

An object of the present invention is the provision of means whereby the carbon-rolls, with their attendant advantages, may be retained, and the feed of the web-plies nevertheless effected in such manner as not to require enlargement of the carbon-carrier, or of the carbon-carrier-supporting struc- 100 105 110

ture, for accommodation of the rolls, and as not to require passage of the web-plies between the carbon-rolls.

In the invention, as embodied in the structure hereinafter described, the web-plies are fed laterally over the supporting structure, forward of the runway thereon for the carbon-carrier, from containers disposed at the sides of the supporting structure; and the carbon-rolls are set transversely of the carbon-carrier within substantially the same space occupied by the carbon-holding blades of the aforesaid Wernery and Smith structure.

15 An object of the invention is the provision of means for guiding the web-plies crosswise of the supporting structure or rearward extension of the platen-carriage, from either or both sides thereof, forward 20 of the carbon-carrier, and for then turning the webs in the direction of the platen, in superposed relation to each other, and interleaved with the carbon-sheets.

25 In this connection, the invention preferably involves a system of web-turning and spacing bars set diagonally over the supporting structure; the bars for handling the webs from one side of the supporting structure being set crosswise and alternated with 30 respect to the bars for handling the webs from the other side of the supporting structure.

35 A feature of the invention is a frame on which the work-web-holders, in the form of spools, magazines or other suitable containers, may be removably mounted; which frame may, itself, be removably attachable to the support for the rearward extension of the platen-carriage, below the platform of such support, with the web-holders arranged at either or both sides thereof.

40 A feature of the invention is a simple and novel device, reliable in action, for locking and unlocking the carbon-roll or rolls, and, 45 where there is a plurality of such rolls, for simultaneously locking and unlocking all of them.

Other features and advantages will hereinafter appear.

50 In the accompanying drawings,

Figure 1 is a top plan view of a platen-carriage, a rearward extension connected thereto, and a carbon-carrier and equipment therefor embodying the present invention.

55 Figure 2 is a view, in side elevation, taken on the line 2—2 of Figure 1, above a stand which supports the typewriting machine.

60 Figure 3 is a view, in side elevation, below the top of the stand which supports the machine, and showing the web-roll or magazine carrier and the connections thereof to the machine support.

65 Figure 4 is a top plan view of the parts shown in Figure 3.

Figure 5 is a view, in front elevation,

taken on the line 5—5 of Figure 1 through the web-roll carrier, and showing the position assumed by the webs in the two extreme positions of the platen-carriage.

70 Figure 6 is a view, in front elevation, taken substantially on the line 5—5 of Figure 1 through the carbon-carrier and its supporting structure.

75 Figure 7 is a view, in front elevation, showing the carbon-carrier rolls and the locking mechanism therefor on the carbon-carrier mechanism.

80 The platen 10, by means of its axle 11, is journaled in side plates 12 of a platen-frame, pivoted at 13 on the side plates 14 of the platen-carriage, to swing up and down between its operative position and a carbon-releasing position. The side plates 12 of the platen-frame have rearward extensions 15, which, when the platen is in 85 operative position, rest upon a shaft or cross-tie 16 connecting the side plates 14 of the carriage. The shaft 16, therefore, supports and determines the operative position 90 of the swinging platen-frame. It is, furthermore, a rock-shaft which carries hooks 17 for locking the shiftable platen-frame in operative position. Coil springs 18 tend to rock the shaft 16 in such direction as to throw the hooks 17 over pins 19 95 on the side plates 12 of the swinging frame, and automatically to lock the swinging frame, as the latter comes to rest upon the shaft 16.

100 An extension 20 on the left-hand hook 17 serves as a finger-piece, whereby to rock the hooks and shaft 16 backward to unlock the frame 12 when the latter is to be lifted to carbon-releasing position. The frame 12 carries a knife 21 for severing the typewritten leading form sections of the web plies; after the carbons have been withdrawn therefrom. The frame 12 also carries a table 22 over which the leading form sections of the web are fed; and the table 22 110 carries a gage arm 23 and gage 24, to which latter the leading edges of the web are drawn when the platen-frame is in carbon-releasing position, for determining the 115 lengths of web to be severed.

120 The platen-carriage is provided with the usual rear paper-table and apron 25 for guiding the webs and carbons down around and to the front of the platen, and with the usual front and rear pressure rolls 26 and 27, respectively. Brackets 28 on the side plates 14 of the carriage support a rod 29 to which are adjustably secured guide-pieces 30 for the side margins of the webs. The webs are led from the carbon-carrier, between the side gages 30, over and around the shaft 16 down to the platen, as shown in Figure 2. The platen-carriage is supported for movement in letter feed and return 125 directions on a rail 31 on the main frame 32 130

of the machine. The machine in its entirety is supported on a supporting stand 33.

The carbon-carrier supporting structure is a substantially rectangular frame, the front cross-piece 34 of which is fixed to and supported by brackets 35 on a bar 36, which forms part of the platen-carriage and connects the side plates of the latter. Depending from the side reaches 37 of the carbon-carrier supporting structure are brackets 38 on which are journaled rollers 39, by means of which the carbon-carrier supporting structure is carried at its rear on a rail 40 for movement with the platen-carriage in letter feed and return directions. The rail 40 is carried by standards 41, preferably connected to the main frame of the typewriting machine, and, like the latter, supported on the top of the typewriter-supporting stand 33.

Rails 42, extending lengthwise of the side reaches 37 of the carbon-carrier supporting structure, provide a runway on which the carbon-carrier is movable, with the carbons, forward step by step as the platen has its line-space movements, and on which the carbon-carrier may be thrown rearward a predetermined distance to withdraw the carbons from the leading form sections 30 of the web after typing on such sections has been completed and the platen-frame thrown to carbon-releasing position. The carbon-carrier comprises a plate 43, see Figures 1, 2 and 7, having journaled 35 on the under side thereof rollers 44, which are grooved to receive the rails 42 and guide the carrier therealong. An arm 45 secured by screws 46 to the left-hand side of the carrier-plate 43 extends forward and terminates in a finger-piece 47 by means of which the operator may throw back the carrier to shift the carbons along the web. Thus far the structure described is not substantially different from that shown in United States 45 Letters Patent to Wernery and Smith, No. 1,132,055, dated March 16, 1915, to which reference may be made for a fuller or more detailed understanding of the operations above mentioned.

The carbon-carrier of the present invention comprises standards 48 and 49 secured by screws 50 to the top of the carrier-plate 43. The carbons, in the form of endless sheets 51^a, 51^b and 51^c, are contained in 55 magazines or wound on spools 52 having axles 53 journaled, one horizontally ahead of the other, in the standards 48 and 49. The bearings for the axles 53 in the standard 48 may be mere holes 54 into which one end of the axles are inserted. In the standard 49, slots 55, extending in from the periphery thereof, are provided to receive the other end of the axles 53 after the first end thereof has been positioned in the standard 48. Hooks 60 65 56 pivoted on the standard 49 are adapted

to be swung over the axles 53, after the latter have been set in the standards, to hold the axles and rolls in place. As shown in Figure 2, the carbon-sheets are preferably led off the under faces of the rolls, and an idler 57, journaled in arms 58 at the forward ends of the standards 48 and 49, may be employed to guide one or more of the carbon-sheets from the level of the lower faces of the rolls to the levels at which the carbon-sheets are fed forward to the platen-frame. 70 75

It will be understood that at the line-feed movements of the platen, the carbon-sheets are not unwound from the rolls. The line-feed movement of the platen, as hereinafter explained, results in the advance of the carbon-carrier along its supporting runway. A sufficient length of carbon-sheet having been drawn from its roll, the roll-carrying means is locked against rotary movement. It is only when the length of carbon-sheet in use has become worn, that the roll is released to rotation to draw off a fresh length therefrom. For holding the rolls normally locked against rotation, each roll has fixed to one end of its axle, shown in the drawings as its right-hand end, a star wheel 59. The teeth of all of the star wheels are arranged to be engaged and locked by teeth 60 on a bar 61, carried on arms 62, pivoted at 63 to standards 64 secured by screws 65 to the carrier-plate 43. The arms 62 may be swung upward on the axis 63 with the bar 61 to lock the axles and carbon-rolls against rotation, and may be swung down to release the axles and rolls when desired. 90 95 100

For thus swinging the lock-bar up and down, an eccentric 66 is provided. This eccentric is carried by an arm 67 pivoted at 68 to a standard 69, see Figure 7, also secured to the carrier-plate 43. The eccentric 66 is set into a yoke or bifurcation formed, in part, by the lock-bar carrying-portion of one of the arms 62 and, in part, by a prong or branch arm 70 therefrom. The normal or roll-locking position of the eccentric arm 67 is determined by contact of a finger 71 thereon with the upper surface of the carrier-plate 43, as shown in Figure 7. 110 115 When, however, by means of a finger-piece 72 on the end of the eccentric arm, the latter is lifted, the eccentric, by turning down upon the branch 70 of the yoke, presses the lock-bar away from the rolls. When the finger-piece 72 is moved in the opposite direction, the eccentric, by pressing up upon the upper branch of the yoke, returns the lock-bar to effective position. In locking position, the eccentric is substantially dead-centered to the pivot 68 of the eccentric arm, so that the lock-bar is held up against gravity drop. 120 125

The work-web-rolls 75 are arranged in tiers, or in any other suitable manner at the sides of the stand 33, below the top thereof, 130

rearward of the typewriting machine, and forward of the runway 42 for the carbon-carrier. In the drawings (see Figure 5), there are two web-rolls at each side of the stand. It will be understood that the web from each roll is to constitute one ply of a multiple web, between the plies of which the carbons from the carbon-supply-rolls 52 are fed to the platen. The plies 76^a, 76^b, 76^c and 76^d from the rolls 75 are, therefore, led into superposed position, as presently to be described. The spools 77, which carry the rolls 75, are journaled in brackets 78 on a roll-holder 79. One of the brackets, illustrated as the forward bracket 78, for each spool 77 (see Figure 3), is perforated to provide a bearing for the axle 80 of the spool. The corresponding or forward end of the spool-axle is set into this perforation, and the opposite or rear end thereof is then dropped into a slot 81 in the opposed bracket, illustrated in the drawings as the rear bracket 78; after which a hook 82, pivoted to the corresponding bracket at 83, is swung down over the rear end of the spool-axle, to retain the spool in its bearings.

The holder for the work-web supply-rolls comprises uprights 84 and 85, at opposite sides of the stand or support 33; to which uprights the brackets 78 are secured. The front and rear uprights, at each side of the holder, are braced and connected by tie-rods 87. At the front and rear ends of the tie-rods 87 are lugs 88, offset laterally, and slotted at 89, to be set onto rods 90, which form part of the stand 33, and which connect the rear legs 91 of the stand with the front legs thereof (not shown). The upper ends of the uprights 84 and 85 are secured by screws 92, threaded into bosses 93, formed on the edges of the top 94 of the stand 33. When, therefore, the screws 92 are loosened, and the work-web roll-holder lifted to clear the lugs 88 of the rods 90, the roll-holder with the rolls may, as a unit, be tilted and withdrawn laterally, in either direction, from the supporting stand.

The webs, at either side of the stand, are led upward from the roll 75, over an idler 95, journaled in brackets 96, secured to the uprights 84 and 85 of the roll-holder. Thence the webs are led upward and over idlers 97 on the sides of an assembling or gathering device, which interleaves the carbons with the work-webs and guides them so assembled to the platen (see Figures 5, 6 and 1). The idlers 97, one at each side of the gathering device, are journaled in brackets 98, secured by screws 99 to the side reaches 37 of the carbon-carrier-supporting structure. As the carbon-carrier-supporting structure is connected to the platen-carriage, to have movement therewith, in letter-feed and return directions, on the rail 40, it and the gathering device mounted thereon and

traveling with it will in one extreme position of the platen assume the full-line position of Figure 5, and in the other extreme position of the platen assume the dotted-line position of Figure 5. When in full-line, Figure 5 position, the web-plies at the left-hand side will be slack, and, when in dotted-line, Figure 5 position, the web-plies at the right-hand side will be slack. To control this slack, there are, journaled on the brackets 96 of the roll-holder 79, idlers 100 opposed to the idlers 95. The webs are led from the rolls between the idlers 95 and 100. The idlers 95 are pressed against the idlers 100 by means of leaf-springs 101, the ends of which are set in between ears 102 on the front and rear brackets 96 and the extended axles 103 of the idlers 95. The axles 103 are set into horizontal slots 104 in the brackets 96, so that the springs 101 may have the action indicated, and so that the idlers 95 and 100 may be forced apart, to permit the webs to be easily threaded therebetween. When the platen-carriage and the assembling and gathering device are sufficiently far to the right or left of center, on either side, the web-plies on that side hang in a loop 105, supported by the corresponding idler 100.

After leaving the idlers 97 at the sides of the gathering device, the web-plies must be spread apart for interleaving therewith of the carbons from the carbon-rolls 52, and must be turned forward at right angles for passage to the platen. For this purpose, a series of obliquely-disposed turning bars 106, numbered also, respectively, 106^a, 106^b, 106^c and 106^d, are provided. The bars 106^a and 106^c, which turn and guide the web-plies 76^a and 76^c, from the right-hand side of the table, extend obliquely from the forward left-hand side of the gathering device to the rear right-hand side thereof, and the turning bars 106^b and 106^d, which turn and guide the web-plies 76^b and 76^d, from the left-hand side of the gathering device, extend obliquely from the forward right-hand side of the gathering device to the rear left-hand side thereof, as shown in Figure 1. Each turning bar, at the rear end thereof, has a bayonet-joint-slot 107, by means of which, as shown in Figures 1 and 6, it is set onto a pin 108, forming an upward extension of a post 109 on the corresponding side reach 37 of the carbon-carrier-supporting structure. The forward end of each turning bar is slotted at 110, axially thereof, to be set into grooves or restricted necks in a corresponding post 111 on the corresponding side reach 37 of the carbon-carrier-supporting structure. The grooves in the post 111 are spaced apart the distances at which it is desired to hold the turning bars spaced from one another. With the turning bar loose, the work-web

ply, therefore, is passed thereover, and then turned forwardly thereunder. The lowermost bar 106^a, with the web thereon, is set upon the shoulder formed by the pin-extension 108 on the right-hand rear post 109, and the bar is moved laterally to cause the pin 108 to be received into the throat of the bayonet-joint-slot 107. The bar is then swung angularly, around the pin 108, until the slot 110 in the forward end thereof is in alignment with the axis of the forward left-hand post 111. The bar, being then level with the lowermost groove in this forward post, is given a translatory movement forward, to cause the post 111 to be received in the slot 110, and to cause the pin 108 to pass to the end of the axially-directed portion of the bayonet-joint-slot at the rear of the bar. The next turning bar 106^b, with the web-ply folded thereover, is then set upon the left-hand post 109 and right-hand post 111 in the same manner; the shoulder formed by the extension 108 on the left-hand post 109 being higher than the corresponding shoulder on the right-hand post 109, to effect the proper spacing of the bar 106^b from the bar 106^a. The bar 106^c is then set on the left-hand post 111 and the right-hand post 109; a collar or washer 112 being slipped over the pin 108 on the right-hand post 109, to maintain proper spacing of the bar 106^c from the bar 106^b. The bar 106^d is then set on the left-hand post 109 and the right-hand post 111, with the spacing collar or washer 112 on the left-hand pin 108 to space the bar 106^d from the bar 106^c. When the bars are all in place and have been pulled forward as far as the bayonet-joint-slots 107 will allow, a thumb-nut 113, threaded on the upper end of each pin 108, is tightened to clamp the bars against displacement.

It will be noted from the foregoing, and from Figure 6, that the web-plies 76^a, 76^b, 76^c and 76^d, on leaving the idlers 97, are passed to different elevations, so that the carbons may be received between the same. If the web-plies were led directly from the idlers 97 to the turning bars 106, they would pass to the latter at different angles, and would, consequently, be made to bear upon the carbon-sheets, which latter are all horizontally directed. In so fouling the carbon-sheets, the forward feed movement of both the carbon-sheets and the work-webs and the rearward withdrawal of the carbon-sheets to succeeding form-sections would be interfered with. Consequently, instead of leading the web-plies directly from the idlers to the oblique turning bars, they are first led over guide-bars 114, each of which extends horizontally, from rear to front, on the level with the turning bar for the web which it is to guide. For simplicity, each guide-bar 114, as shown in Figure 1, is formed as a unit with the corresponding turning bar 106. The guide-bars 114 connect at their rear with the turning bars, and at their forward ends are free. The free ends of the guide-bars are supported in the following manner. The lowermost guide-bar 114, at its forward end (see Figures 1 and 6), rests upon the upper end of a stud 115, threaded into a lug 116 on the right-hand side reach 37 of the carbon-carrier-supporting structure. The forward free end of the next higher guide-bar 114 rests upon a stud 117 on and near the front end of the turning bar 106^a. Studs 118 and 119 (see Figure 6), on and near the front ends of the turning bars 106^b and 106^c, support the forward free ends of the two higher guide-bars 114. To guide the carbons 51^a, 51^b and 51^c, from the rear of the machine, in a similar way, there are provided guide-bars 114^a extending from the turning bars 106, and resting on studs 114^b of the oppositely-disposed turning bars 106.

Guides or gages 120 are provided for the side edges of the webs between the idlers 97 and the guide-bars 114. These guides 120 are shown as fingers (see Figures 1, 2 and 6), projecting upward from slides 121 on the side reaches 37 of the carbon-carrier-supporting structure. Slides, instead of fixed brackets, are provided, in order that the guides 120 may be adjusted to accommodate webs of different widths. Thumbscrews 122, passing through horizontal slots 123 in the slides, in part support the slides, and serve, when tightened, to hold the slides in adjusted position. Pins 124 on the side reaches 37 project into the slots 123, to prevent angular displacement of the slides and guide-fingers.

In interleaving the carbons with the work-web plies, and in adjusting the work-web plies and carbons preliminary to typewriting, the lower work-web is threaded from its roll 75 or magazine, over its oblique turning bar 106^a, and the leading end thereof led forward of the turning bar in the manner hereinbefore described. The rearmost carbon-carrier-spool 52 being unlocked, the sheet therefrom is drawn forward over the leading end of the lowermost web. The web 76^b is then superposed on this lowermost carbon-sheet, and the carbon from the central carbon-roll drawn forward thereover. The work-web 76^c is then positioned over the middle carbon, and the carbon from the forward roll 52 led thereover. After the upper work-web has been positioned over the upper carbon, and all the carbon-carrier rolls being unlocked, the work-webs and the carbons are seized and drawn forward to the position for printing on the leading web-form. The carbon-carrier-spoils are then locked, and the carbon-carrier given a rearward throw sufficient to

draw the leading ends of the carbons slightly rearward of the leading ends of the work-webs, so that, in subsequent operation, the leading ends of the work-webs may be 5 pinched together without pinching the carbons. This adjustment of the work-webs and carbons may be effected when the platen-frame 12 is in carbon-releasing position. Thereafter the carbon-carrier is set for the 10 throw determined by the length of the form-sections. The operations of the typewriting machine may then be as explained in the Wernery and Smith patent, hereinbefore referred to. The length of carbon in use having, however, become worn, the carbon-carrier-spools are unlocked, the carbons drawn forward a distance sufficient to provide fresh printing surfaces, and the worn length of the carbons detached.

20 It will be noted, from the foregoing, that the position of the work-web supply-rolls is such that the plies thereof do not pass over, around or between the carbon-supply rolls, and that, consequently, the latter may 25 be of such size as not to require constant replacement. It will also be noted that the arrangement and feed of the work-web-rolls and plies is such that the carbon-rolls may be set substantially horizontally and transversely, and at the same level on the carbon-carrier, within the lines defined by the sides 30 of the work-web in the forward movement of the latter to the platen. Thus, no lateral extension of the carbon-carrier, or of the 35 carbon-carrier-supporting structure, is required, such as would add to the weight thereof, and, consequently, throw such a burden on the platen-carriage and carbon-carriage-drive as to make this drive sluggish or unreliable in action.

40 It will be further noted that the carbon-carrier and carbon-rolls are arranged substantially unitary with the typewriting machine. That is to say, they are mounted 45 directly thereon. They are carried by and move with a moving element of the apparatus. They maintain a fixed relation of alignment to this carrying element of the apparatus, to the work-web, and the elements 50 upon which the work-web is carried and by which it is controlled. This method of mounting the carbon-rolls permits the carbon-sheets drawn therefrom to be led into interleavement with the work-webs in a direct substantially straight line and in planes 55 substantially parallel to each other and to the planes of the work-webs, after the latter are directed toward the platen. For this reason, since, in the typing or other operation 60 of the machine, no turning or other undesirable change of direction of travel of the carbon-sheets is necessary, the strain upon these sheets and the risk that they will thereby become torn or displaced is reduced 65 to a minimum. Consequently, the carbon-

70 sheets may be made of extremely thin and delicate texture, and thereby effect an added efficiency in the apparatus. It will be noted that in the present arrangement it is the work-web, and not the carbon-web, which is led laterally onto the assembling or gathering device, and there obliquely turned and directed over turning bars toward the platen. It is during this operation of directing the work-web over the oblique turning 75 bars, that the web, being turned, might become torn; and hence, since the work-web is usually of heavier and coarser texture than the carbon-web, the probability of its being torn in such an operation is much 80 less than if it were the carbon thus being turned. It must be evident from the above that the arrangement and relation of carbon to work-web provided in this apparatus is a distinct advance in the art, which embodies substantial advantages in this respect. 85 Also, the interleavement of the carbon-web with the work-web as accomplished in this apparatus reduces the possibility of improper registry of the work-webs and of any 90 undesirable marking of the work-web by the carbon-web, which heretofore, at times, resulted from the weaving action of the carbon-web because of its passage through the carbon-carrier from a source of supply entirely outside of the machine.

95 Variations may be resorted to within the scope of the invention, and portions of the improvements may be used without others.

Having thus described my invention, I 100 claim:

1. In a typewriting machine having a letter-feeding carriage and a platen thereon, said carriage having a rearward extension, stationary spools of work-web disposed at 105 opposite sides of said rearward extension and below the carriage, delivering work-webs upwardly and in opposite directions to said extension, oblique devices crosswise of each other and stationary on said extension for directing said work-webs forwardly to said platen, carbon-sheets interleaved with the work-webs, and reciprocable means for stripping the carbon-sheets from the work-webs.

110 2. In a typewriting machine having a letter-feeding carriage and a platen thereon, said carriage having a rearward extension, stationary spools of work-web disposed at 115 opposite sides of said rearward extension and below the carriage, delivering work-webs upwardly and in opposite directions to said extension, oblique devices crosswise of each other on said extension for directing said work-webs forwardly to said platen, and posts or supporting means for holding the oblique devices in operative relation on said extension, said oblique devices being recessed for removable attachment to 120 said supporting posts.

3. The combination with a typewriting machine, of a gathering device at the rear thereof, a web-container at the side of the gathering device, means for guiding the web from the container onto the gathering device crosswise thereof, a bar, set diagonally of the gathering device, and around which the web may be turned, for directing the web forward toward the platen, and posts for holding the bar at its ends; the bar having a bayonet-joint at one end for engagement with one post and having a recess at its other end for engagement with the other post, so that the bar may be positioned by swinging the same around the post at the bayonet-joint until the same is in alignment with the other post, and then given a translatory movement to interlock the same with both posts.
- 10 4. The combination with a typewriting machine, of a gathering device at the rear thereof, a web-container at the side of the gathering device, means for guiding the web from the container onto the gathering device crosswise thereof, a bar, set diagonally of the gathering device, and around which the web may be turned, for directing the web forward toward the platen, posts for holding the bar at its ends; the bar having a bayonet-joint at one end for engagement with one post and having a recess at its other end for engagement with the other post, so that the bar may be positioned by swinging the same around the post at the bayonet-joint until the same is in alignment with the other post, and then given a translatory movement to interlock the same with both posts, and a set screw threaded into one post to be tightened against the bar in the home position of the latter.
- 20 5. In a typewriting machine having a letter-feeding carriage and a platen thereon, said carriage having a rearward extension, sources of supply of work-web disposed at opposite sides of said rearward extension and delivering work-webs in opposite directions thereto, oblique devices on said extension for directing said work-webs forwardly to said platen, a shiftable carbon-carrier traveling on said extension in the rear of said work-webs, and carbon-rolls or magazines in the rear of said oblique devices, mounted on said carbon-carrier and moving therewith, the carbon-webs extending forwardly from said rolls between the work-webs advancing to the platen.
- 30 6. The combination with a typewriting machine having a letter-feeding rotary platen and a carriage for said platen, having a rearward extension, of a gathering device on said extension, a plurality of work-web containers or magazines disposed at the sides of said gathering device, means for guiding the work-webs in superposed relation onto the gathering device, in opposite directions, crosswise thereof, means stationary on the gathering device for turning the work-webs, and guiding the same, forward toward the platen, a carbon-sheet-holder at the rear of the gathering device, means for guiding carbon-sheets forward therefrom into interleaving with the work-webs, and reciprocal means for stripping the carbon-sheets interleaved with the work-webs.
- 40 7. In a typewriting machine having a letter-feeding carriage and a platen thereon, said carriage having a rearward extension, a gathering device on said extension, a plurality of work-web containers or magazines disposed at the side of said gathering device and below the level thereof, delivering work-webs upwardly and in opposite directions to said gathering device, means for guiding the work-webs in superposed relation onto the gathering device from opposite directions and crosswise thereof, oblique devices for turning the work-webs and guiding them forwardly from said gathering device toward the platen, a shiftable carbon-carrier traveling on said extension and at the rear of said gathering device, and carbon-rolls or magazines mounted on said carbon-carrier and moving therewith, the carbon-webs extending forwardly from said rolls toward the platen into interleaving with the work-webs.
- 50 8. The combination of a typewriting machine having a letter-feeding carriage and a platen thereon, said carriage having a rearward extension, a source of supply of work-webs disposed at opposite sides of said rearward extension and delivering webs in opposite directions thereto, obliquely-disposed bars for each work-web set crosswise and in superposed relation to each other on said extension for turning said webs and directing them forwardly toward the platen, a shiftable carbon-carrier traveling on said extension in the rear of said work webs, and a carbon-roll or magazine in the rear of said obliquely-disposed bars mounted on said carbon-carrier, moving therewith and carrying one or more independent layers of carbon-sheets, the respective sheets or layers of carbon-web being delivered from said roll to and interleaved between the corresponding work-webs advancing to the platen.
- 60 9. In a typewriting machine having a letter-feeding carriage and a platen thereon, said carriage having a rearward extension, a gathering device on said extension, a plurality of work-web containers or magazines disposed at the sides of said gathering device and below the level thereof, delivering work-webs upwardly and in opposite directions to said gathering device, a shiftable carbon-carrier traveling on said extension and at the rear of said gathering device, carbon-rolls or magazines

mounted on said carbon-carrier and moving therewith, means for guiding carbon-sheets from said carbon-rolls forwardly over said extension and to said gathering device 5 toward the platen, means for separating said work-webs and directing them in planes spaced apart and substantially parallel to the planes of the carbon-sheets crosswise of the gathering device, and means on 10 said gathering device obliquely disposed to said work-webs for turning and guiding said work-webs toward the platen with the carbon-sheets interleaved therebetween.

10. In a typewriting machine having a letter-feeding carriage and a platen thereon, said carriage having a rearward extension, a gathering device on said extension, a plurality of work-web containers or magazines disposed in a tier below and at opposite 15 sides of said gathering device, delivering work-webs upwardly and in opposite directions to said gathering device, an idler for directing said webs to said gathering device, a shiftable carbon-carrier traveling on said 20 extension and at the rear of said gathering device, carbon-rolls or magazines mounted in substantially the same horizontal plane on said carbon-carrier and moving therewith, means for guiding carbon-sheets from 25 said carbon-rolls forwardly over said extension and to said gathering device toward the platen, means for separating said work-webs and directing them in planes spaced apart and parallel to the planes of the carbon-sheets crosswise of the gathering device, and means on 30 said gathering device obliquely disposed to said work-webs for turning and guiding said work-webs toward the platen with the carbon-sheets interleaved therebetween.

11. The combination with a typewriting machine having a rotary platen and means for effecting line-space rotary movement of the platen, of a carriage for said platen 45 having a rearward extension, a carrier movable on said rearward extension toward and from the platen, a plurality of spools or cylinders on the carrier for holding rolls of carbon-paper, means for holding the forward ends of the carbon-sheets to the platen for line-space forward movement of the carbon-sheets and carbon-carrier with the platen, and means for feeding work-webs laterally into interleavement with the carbon-sheets, between the carbon-carrier and the platen, and for turning the work-webs, thus interleaved with the carbon-sheets, in the direction of the platen.

12. The combination with a typewriting 60 machine having a rotary platen and means for effecting line-space rotary movement of the platen, of a carriage for said platen having a rearward extension, a carbon-sheet holder at the rear of the rearward extension supported thereon for movement with

the platen-carriage in letter-feed and return directions and movable on said extension toward and from the platen, means for holding the forward ends of carbon-sheets to the platen for line-space forward 70 movement of the carbon-sheets and carbon-sheet holder with the platen, and means for feeding work-webs laterally into interleavement with the carbon-sheets between the carbon-sheet holder and the platen and for turning the work-webs thus interleaved with the carbon-sheets in the direction of the platen.

13. The combination with a typewriting machine having a rotary platen and means 80 for effecting line-space rotary movement of the platen, of a carriage for said platen having a rearward extension, a carrier movable on said rearward extension toward and from the platen, a plurality of spools or 85 cylinders, arranged horizontally one behind the other, on the carrier for holding rolls of carbon-paper, means for holding the forward ends of the carbon-sheets to the platen for line-space forward movement of the carbon-sheets and carbon-carrier with the platen, and means for feeding work-webs of paper laterally into interleavement with the carbon-sheets, between the carbon-carrier and the platen, and for turning the work-webs, thus interleaved with the carbon-sheets, in the direction of the platen.

14. The combination with a typewriting machine having a rotary platen and means for effecting line-space rotary movement of the platen, of a carriage for said platen having a rearward extension, a carrier movable on said extension toward and from the platen, a plurality of spools or cylinders arranged horizontally one behind another on 100 the carrier for holding rolls of carbon-paper, said carrier and spools being movable with the platen and platen-carriage in both letter-feed and return directions and line-feed and return directions, means for holding the forward ends of the carbon-sheets to the platen for line-space forward movement of the carbon-sheets and carbon-carrier with the platen, and obliquely-disposed means for feeding work-webs of paper laterally into interleavement with the carbon-sheets between the carbon-carrier and the platen and for turning the paper work-webs thus interleaved with the carbon-sheets in the direction of the platen.

15. The combination with a typewriting machine having a rotary platen and means for effecting line-space rotary movement of the platen, of a carriage for said platen having a rearward extension, a carrier movable 115 on said rearward extension toward and from the platen, a plurality of spools or cylinders on the carrier for holding rolls of carbon-paper, means for locking the cylinders against rotation, means for holding the 120

forward ends of the carbon-sheets to the platen for line-space forward movement of the carbon-sheets and carbon-carrier with the platen, when the cylinders are locked, and means for feeding work webs laterally into interleavement with the carbon-sheets, between the carbon-carrier and the platen, and for turning the work-webs, thus interleaved with the carbon-sheets, in the direction of the platen.

16. The combination with a typewriting machine having a rotary platen and means for effecting line-space rotary movement of the platen, of a carriage for said platen having a rearward extension, a carrier movable on said rearward extension toward and from the platen, a plurality of spools or cylinders on the carrier for holding rolls of carbon-paper, means for holding the forward ends of the carbon-sheets to the platen for line-space forward movement of the carbon-sheets and carbon-carrier with the platen, web-containers mounted at the side of said rearward extension, and means for feeding work-webs laterally, from the web-containers onto said rearward extension, into interleavement with the carbon-sheets, between the carbon-carrier and the platen, and for turning the work-webs, thus interleaved with the carbon-sheets, in the direction of the platen.

17. The combination with a typewriting machine having a rotary platen and means for effecting line-space rotary movement of the platen, of a carriage for said platen having a rearward extension, a carrier movable on said rearward extension toward and from the platen, a plurality of spools or cylinders on the carrier for holding rolls of carbon-paper, means for holding the forward ends of the carbon-sheets to the platen for line-space forward movement of the carbon-sheets and carbon-carrier with the platen, a tier of web-containers on each side of said rearward extension, between the runway for the carbon-carrier and the platen, and means for feeding work-webs laterally, from the web-containers onto said rearward extension, into interleavement with the carbon-sheets, and for turning the work-webs, thus interleaved with the carbon-sheets, in the direction of the platen.

18. The combination with a typewriting machine having a rotary platen and means for effecting line-space rotary movement of the platen, of a carriage for said platen having a rearward extension, a carrier movable on said rearward extension toward and from the platen, a plurality of spools or cylinders on the carrier for holding rolls of carbon-paper, a toothed wheel fast to each spool or cylinder, a bar having teeth thereon for simultaneous engagement with the several toothed wheels to lock the spools or cylinders against rotation, means for

throwing the bar into and out of engagement with the toothed wheels, means for holding the forward ends of the carbon-sheets to the platen for line-space forward movement of the carbon-sheets and carbon-carrier with the platen, when the cylinders are locked, and means for feeding work-webs into interleavement with the carbon-sheets.

19. The combination with a typewriting machine having a rotary platen and means for effecting line-space rotary movement of the platen, of a carrier for said platen having a rearward extension, a carrier movable on said rearward extension toward and from the platen, a plurality of spools or cylinders on the carrier for holding rolls of carbon-paper, a toothed wheel fast to each spool or cylinder, a bar having teeth thereon for simultaneous engagement with the several toothed wheels to lock the spools or cylinders against rotation, an eccentric for throwing the bar into and out of engagement with the toothed wheels, means for holding the forward ends of the carbon-sheets to the platen for line-space forward movement of the carbon-sheets and carbon-carrier with the platen, when the cylinders are locked, and means for feeding work-webs into interleavement with the carbon-sheets.

20. The combination with a typewriting machine having a rotary platen and means for effecting line-space rotary movement of the platen, of a carriage for said platen having a rearward extension, a carrier movable on said rearward extension toward and from the platen, a plurality of spools or cylinders on the carrier for holding rolls of carbon-paper, means for holding the forward ends of the carbon-sheets to the platen for line-space forward movement of the carbon-sheets and carbon-carrier with the platen, a plurality of containers for work-webs in fixed position at the side of the rearward extension, and means for feeding the work-webs from the containers laterally into interleavement with the carbon-sheets.

21. The combination with a typewriting machine having a rotary platen, a carriage for and movable with the platen in letter-feed and return directions, and means for effecting line-space rotary movement of the platen, of a rearward extension of said platen-carriage having movement with the latter, a carrier movable on said rearward extension toward and from the platen, a plurality of spools or cylinders on the carrier for holding rolls of carbon-paper, means for holding the forward ends of the carbon-sheets to the platen for line-space forward movement of the carbon-sheets and carbon-carrier with the platen, and means for feeding work-webs laterally into interleavement with the carbon-sheets, be-

tween the carbon-carrier and the platen, and for turning the work-webs, thus interleaved with the carbon-sheets, in the direction of the platen.

- 5 22. The combination with a typewriting machine having a rotary platen, a carriage movable with the platen in letter-feed and return directions, and means for effecting line-space rotary movement of the platen, 10 of a rearward extension of the machine connected to the platen-carriage for movement with the latter, a carrier mounted thereon, movable therewith in letter-feed and return directions and movable on said 15 rearward extension toward and from the platen, a plurality of spools or cylinders on the carrier for holding rolls of carbon-sheets, means for holding the forward ends of the carbon-sheets to the platen for line- 20 space forward movement of the carbon-sheets and carbon-carrier with the platen, and means for feeding work-webs laterally into interleavement with the carbon-sheets, 25 between the carbon-carrier and the platen, and for turning the work-webs, thus interleaved with the carbon-sheets, in the direction of the platen.

23. The combination with a typewriting machine having a rotary platen, a carriage 30 for and movable with the platen in letter-feed and return directions, and means for effecting line-space rotary movement of the platen, of a rearward extension of said platen-carriage having movement with the latter, a carrier movable on said rearward extension toward and from the platen, a plurality of spools or cylinders on the carrier for holding rolls of carbon-paper, means for holding the forward ends of the 35 carbon-sheets to the platen for line-space forward movement of the carbon-sheets and carbon-carrier with the platen, a support for the typewriting machine and rearward extension, a plurality of containers for 40 work-webs located on the support between the platen and the runway for the carbon-carrier, laterally of the latter, and means for feeding the work-webs from the containers laterally into interleavement with the carbon-sheets, and for turning the work-webs in the direction of the platen.

24. In a typewriting machine, a platen, a rotary spool or cylinder for holding a 45 continuous sheet in the form of a roll, a toothed wheel connected to the cylinder to rotate therewith, a bifurcated or yoke-shaped member carrying a tooth for engagement with the teeth of the wheel to lock the cylinder against rotation, an eccentric set in such bifurcation or yoke in engagement with the branches thereof, and means for turning the eccentric to lock and unlock the cylinder.

25. In a typewriting machine, a platen, 50 a rotary spool or cylinder for holding a con-

tinuous sheet in the form of a roll, a toothed wheel connected to the cylinder to rotate therewith, a bifurcated or yoke-shaped member carrying a tooth for engagement with the teeth of the wheel to lock the cylinder against rotation, an eccentric set in such bifurcation or yoke in engagement with the branches thereof, and an arm pivoted co-axially with the eccentric and secured thereto for turning the eccentric to lock and unlock the cylinder.

26. In a typewriting machine, a platen, a rotary spool or cylinder for holding a continuous sheet in the form of a roll, a toothed wheel connected to the cylinder to rotate therewith, a bifurcated or yoke-shaped member carrying a tooth for engagement with the teeth of the wheel to lock the cylinder against rotation, an eccentric set in such bifurcation or yoke in engagement with the branches thereof, and means for turning the eccentric to lock and unlock the cylinder, the eccentric being dead-centered in cylinder-locking position to prevent unintended release of the cylinder.

27. In a typewriting machine, a platen, a rotary spool or cylinder for holding a continuous sheet in the form of a roll, a toothed wheel connected to the cylinder to rotate therewith, a pivoted, bifurcated, or yoke-shaped, member carrying a tooth for engagement with the teeth of the wheel to lock the cylinder against rotation, an eccentric set in such bifurcation or yoke in engagement with the branches thereof, and means for turning the eccentric to lock and unlock the cylinder.

28. In a typewriting machine, a platen, a rotary spool or cylinder for holding a continuous sheet in the form of a roll, a support for the cylinder, a toothed wheel connected to the cylinder to rotate therewith, a bifurcated or yoke-shaped member carrying a tooth for engagement with the teeth of the wheel to lock the cylinder against rotation, an eccentric set in such bifurcation or yoke in engagement with the branches thereof, an arm pivoted co-axially with the eccentric and secured thereto for turning the eccentric to lock and unlock the cylinder, and a finger on the eccentric-arm to determine the locking position of the eccentric by engagement with the cylinder-support.

29. In a typewriting machine having a letter-feeding carriage and a platen thereon, said carriage having a rearward extension, a shiftable carbon-carrier traveling on said extension from the rear thereof, a plurality of rotary spools or cylinders for holding continuous carbon-sheets in the form of rolls mounted on said carbon-carrier in a substantially horizontal plane, a toothed wheel connected to each cylinder to rotate there-

with, a bar substantially horizontal adjacent the toothed wheels and having teeth for engagement therewith to lock the cylinders against rotation, pivoted arms on which the bar is carried, and an eccentric for swinging the pivoted arms to lock and unlock the cylinders.

30. In a typewriting machine having a letter-feeding carriage and a platen thereon, said carriage having a rearward extension, a shiftable carbon-carriage traveling on said extension, a plurality of rotary spools, cylinders or magazines arranged in substantially the same horizontal plane on said carbon-carrier for holding continuous sheets of carbon, a toothed wheel connected to each cylinder to rotate therewith, a substantially horizontal bar adjacent the toothed wheels having teeth for engagement therewith to lock the spools or cylinders against rotation, pivoted arms on which the bar is carried, and an eccentric for vertically swinging said pivoted arms to lock and unlock said cylinders or spools.

31. The combination with a typewriting machine having a letter-feeding carriage and a platen thereon, said carriage having a rearward extension, of a gathering device carried on said rearward extension and over which work-webs may be fed forward to the platen of the machine, a work-web holder, means for supporting said work-web holder at opposite sides of and below said gathering device, spools or cylinders journaled on the web-holder on opposite sides of said gathering device, means for guiding the work-webs from said cylinders crosswise of said gathering device, and means obliquely disposed to said work-webs and mounted on said gathering device for turning the work-webs coming from the opposite sides and directing them forward toward the platen in superposed relation.

32. The combination with a typewriting machine having a rotary platen and a letter-feeding carriage for said platen having a rearward extension, of a gathering device mounted on said rearward extension over which work-webs may move and be turned forward to the platen of the machine, work-web containers below and at opposite sides of said gathering device, idlers on opposite sides of said gathering device between and by means of which work-web plies are led up and crosswise over said gathering device from opposite directions, and oblique devices disposed crosswise on said gathering device for turning the work-webs from opposite sides and directing them forwardly to the platen in superposed relation.

33. The combination with a typewriting machine having a rotary platen and a carriage for said platen having a rearward extension, of a gathering device mounted on

said rearward extension over which work-webs travel crosswise and are turned forward to the platen of the machine, work-web containers at opposite sides of said gathering device, idlers on opposite sides of said gathering device between and by means of which work-web plies are led up and crosswise over said gathering device from opposite directions, guide-bars on said gathering device for separating the work-webs presented at the same side of the gathering device and directing them in substantially parallel planes across said device, and oblique devices on said gathering device for turning the work-webs from opposite sides and directing them forwardly to the platen in superposed relation.

34. The combination with a typewriting machine having a rotary platen and a carriage for said platen having a rearward extension, of a gathering device mounted on said rearward extension over which work-webs may move crosswise and be turned forward to the platen of the machine, work-web containers at opposite sides of said gathering device, a pair of idlers on opposite sides of said gathering device between and by means of which work-web plies are led up and crosswise over said gathering device from opposite directions, means for yieldingly holding together the idlers of each pair, and oblique devices on said gathering device for turning the work-webs from opposite sides and directing them forwardly to the platen in superposed relation.

35. The combination with a typewriting machine, of a supporting structure over which webs may run forward to the platen of the machine, web-containers disposed at opposite sides of said supporting structure, and a pair of idlers disposed at correspondingly opposite sides of the structure between and by means of which the webs are led crosswise over the structure from opposite directions; the structure being connected to the platen-carriage of the typewriting machine to have movements in letter-feed and return directions with the latter, and the idlers serving to control and support the slack in the webs due to such movements, oblique means being provided to change the direction of the work-webs forwardly.

36. The combination with a typewriting machine having a platen and a carriage therefor with a supporting structure rearwardly extending therefrom, of a gathering device on said structure over which work-webs may run forward to the platen of the machine, a plurality of work-web spools, magazines or containers disposed at opposite sides of said gathering device and below said supporting structure, conveying, separating and guiding means for direct-

- ing the work-webs into superposed relation crosswise over said gathering device, obliquely-arranged bars disposed crosswise in said gathering device for turning the work-webs forward thereon, and bars unitary with the oblique bars for separating the webs and directing them in parallel planes as they are received with the gathering device.
37. The combination with a typewriting machine, of a gathering device over which webs may be fed to the platen of the machine, and guides or gages on said gathering device, for the side edges of the webs, consisting of fingers, slides having pin-and-slot connections with the gathering device and carrying the fingers, for adjustment of the fingers to different widths of web, other pins set into the slots to prevent angular displacement of the slides and fingers, and means for locking the slides.
38. The combination with a typewriting machine, of a gathering device over which webs may be fed to the platen of the machine, and guides or gages on the gathering device, for the side edges of the webs, consisting of fingers, slides having pin-and-slot connections with the gathering device and carrying the fingers, for adjustment of the fingers to different widths of web, other pins set into the slots to prevent angular displacement of the slides and fingers, and means for locking the slides, consisting of a thumb-nut threaded onto one pin in each slot.
39. In a typewriting machine, the combination of a carriage, a platen on said carriage, a rearwardly-extending supporting structure connected to and traveling with said carriage, a gathering device on said supporting structure over which work-webs may run forward to the platen of the machine, work-web spools, magazines or containers disposed at opposite sides of said supporting structure and below said gathering device, conveying, separating and guiding means for directing the work-webs into superposed relation crosswise over said gathering device, obliquely-arranged devices disposed crosswise in said gathering device to guide and turn the work-webs at right angles to themselves from the gathering device toward the platen, a shiftable carbon-carrier traveling on said rearwardly-extending supporting structure, a source of carbon-sheet supply mounted on said carbon-carrier and moving therewith, and means for guiding carbon-sheets from said source of supply forwardly interleaved with those portions of the work-webs directed to the platen by the gathering device.
40. In a typewriting machine, the combination of a carriage, a platen on said carriage, a rearward extension of said carriage to travel therewith, work-web containers or magazines at the sides of the machine, means to guide the work-webs onto said rearward extension, means to guide the work-webs at right angles to themselves from said rearward extension toward the platen, means to support a carbon-sheet supply-roll, means for guiding a carbon-sheet from the supply-roll and between those portions of the work-webs directed to the platen, means to feed the carbon-sheet with the work-webs, and means for shifting the carbon-sheet to fresh portions of the work-webs.
41. In a typewriting machine, the combination of a carriage, a platen on said carriage, a rearward extension of said carriage movable therewith, a gathering device on said extension of said carriage to travel therewith, work-web containers or magazines at the sides of the machine, means to guide the work-webs onto the gathering device, obliquely-disposed guide-bars to guide the work-webs at right angles to themselves from the gathering device toward the platen, means disposed behind said guide-bars to support a carbon-sheet, means for guiding the carbon-sheet from its support and between those portions of the work-webs directed to the platen, means to feed the carbon-sheet with the work-webs, and means for shifting the carbon-sheet to fresh portions of the work-webs.
42. In a typewriting machine, the combination of a carriage, a rearward extension of said carriage movable therewith, a gathering device on said extension of said carriage to travel therewith, a fixed supporting frame, work-web containers at the sides of the machine and below the path of travel of said gathering device, and means to conduct the webs upwardly from said containers to and over the sides of said gathering device.
43. In a typewriting machine, the combination of a carriage, a platen on said carriage, a rearward extension of said carriage movable therewith, a gathering device on said extension to travel with said carriage and extension, a work-web supply container or magazine at the side of said gathering device, means to guide a work-web from said container or magazine onto said gathering device, an obliquely-disposed guide-bar over which the work-web is folded to conduct it at right angles of itself and toward the platen, side-edge guides for said work-web between the container or magazine and the guide-bar, and side-edge guides between said guide-bar and said platen for said work-web.
44. In a typewriting machine, the combination of a carriage, a platen on said carriage, a rearward extension of said carriage movable therewith, a gathering device on said extension of said carriage to travel

therewith, work-web supply containers or magazines, one at each side of said gathering device, means to guide work-webs from said containers or magazines onto said gathering device, obliquely-disposed guide-bars on said gathering device, over which the work-webs are folded to conduct them at right angles of themselves and toward the platen, adjustable side-edge guides for 10 said work-webs between the containers or magazines and the guide-bars, and adjustable side-edge guides for said work-webs between said guide-bars and said platen.

45. In a typewriting machine, the combination of a carriage, a platen on said carriage, a rearward extension of said carriage movable therewith, a gathering device on said extension of said carriage to

travel therewith, a fixed supporting frame, work-web supply containers or magazines, 20 one at each side of said table and supported on said supporting frame, means to guide work-webs from said containers or magazines over the sides of and onto said gathering device, obliquely-disposed guide-bars on 25 said gathering device over which the work-webs are folded to conduct them at right angles of themselves and toward the platen, side-edge guides on said gathering device to guide said work-webs from the containers 30 or magazines to the guide-bars, and side-edge guides on said carriage to guide said work-webs from said guide-bars to said platen.

JOHN WALDHEIM.
